UNITED STATES PATENT OFFICE.

FRANK S. SPRAGUE, OF BOSTON, MASSACHUSETTS.

SPRING BED-BOTTOM OR MATTRESS.

SPECIFICATION forming part of Letters Patent No. 689,240, dated December 17, 1901.

Application filed June 29, 1901. Serial No. 66,596. (No model.)

To all whom it may concern:

Be it known that I, FRANK S. SPRAGUE, a citizen of the United States, residing at and whose post-office address is No. 95 Beverly 5 street, Boston, in the county of Suffolk and State of Massachusetts, have invented new and useful Improvements in Spring Bed-Bottoms or Mattresses, of which the following is a specification.

10 This invention relates to new and useful improvements in spring bed-bottoms or mattresses; and its primary object is to provide a device of this character having novel devices for adjusting the tension of the springs 15 without the necessity of employing tools.

A further object is to so construct the frame of the bed-bottom as to permit the same to be readily folded when desired.

With these and other objects in view the 20 invention consists in the novel construction, combination, and arrangement of parts, which will be hereinafter fully described, illustrated in the accompanying drawings, and particularly pointed out in the appended claims.

25 In the drawings, Figure 1 is a plan view of the mattress, showing the locking-sleeves in section. Fig. 2 is a side elevation of the folded mattress. Fig. 3 is an enlarged longitudinal section through the adjacent ends of 30 one side of the frame and through the sleeve, and Fig. 4 is a detail view of said ends folded upon each other.

Referring now to the drawings by reference-numerals, 11 are similar sections, which when 35 put together form the frame of the mattress. These sections are formed of tubing, and in the ends of one section is fitted a plug 2, having an annular flange 3, which serves to limit its inward movement. This plug is provided 40 with a threaded passage, which receives a screw 4, the head 5 of which is swiveled in a cylindrical block 6. The ends of the remaining sections 1 of the frame are closed, as shown at 7, Fig. 3, and are slotted, as at 8. A link 45 9 is loosely mounted in each slot and engages the adjacent block 6.

Sleeves 10 are slidably mounted on the sides of the mattress-frame and are adapted when extending over the ends of the two sections 1 50 to hold said frame rigidly in extended position. A bolt 11 passes through this sleeve and through the screw 4, and it is obvious that

when the sleeve is turned the screw will be revolved therewith, thereby moving the ends of the sections 11 from or toward each other. 55 Lugs 12 are arranged on one section 1 near its ends and serve to limit the movement of the sleeves 10 in one direction. Set-screws 13 are employed on the sleeves 10 and are adapted to lock the sleeves in the positions to which 60 they are moved.

A spring-metal fabric 14 is secured to the ends of the mattress-frame, and when it is desired to tighten the same it is only necessary to turn the sleeves 10 manually. This will 65 turn screws 4 and force the sections 1 from each other. The screws 13 are set against the sections 1, and the mattress is then ready for use.

If for any reason it is desirable to fold the 70 mattress, the screws 13 are loosened and the sleeves 10 and screws 4 are revolved, so as to slack the fabric 14. The bolts 11 are then removed and the sleeves slid off of one of the sections 1. The links 9 serve as hinges, and 75 the frame can thus be readily folded. The lugs 12 are so located that when the sleeves 10 abut thereagainst the bolts 11 inserted in said sleeves will pass directly into the apertures in the screws 4. 80

It will be seen that the device is extremely simple and durable and that it can be tensioned or folded without the use of any tools.

In the foregoing description I have shown the preferred form of my invention; but I do 85 not limit myself thereto, as I am aware that modifications may be made therein without departing from the spirit or sacrificing any of the advantages thereof, and I therefore reserve the right to make all such changes as 90 fairly fall within the scope of my invention.

Having thus described my invention, what I claim, and desire to secure by Letters Patent, is—

1. In a device of the character described the 95 combination with frame-sections of a swiveled screw hinged to one section and adapted to engage the remaining section, a sleeve mounted upon the sections, and means for securing the screw and sleeve together. 100

2. In a device of the character described the combination with frame-sections, of a block hinged to one section, a screw swiveled therein and adapted to engage the remaining section,

a slideable and revoluble sleeve mounted on the sections, detachable means for rigidly securing the sleeve to the screw, a set-screw for locking the sleeve in adjusted position, and 5 means for limiting the longitudinal movement of the sleeve.

3. In a folding mattress, the combination with frame-sections; of blocks between said sections, link connections between the blocks 10 and the ends of one section, a rigid connec-

tion between the blocks and the ends of the remaining section, and means for adjusting said blocks from and toward said remaining section.

In testimony whereof I affix my signature 15 in presence of two witnesses.

FRANK S. SPRAGUE.
